COIN METER WITH SET CYCLE

Harry Greenwald, Blauvelt, N. Y., assignor to
Rebco Corporation, New York, N. Y., a corpora-
tion of New York

Application March 7, 1950, Serial No. 148,163

3 Claims. (Cl. 161—4)

1

This invention relates to new and useful improvements in coin meters with set cycles. These meters are generally used on any circuit or appliance where a reset feature and a time change by the operator is not required.

The dominating object of this invention resides in the construction of a coin meter with a set cycle, which is exceptionally simple and which may be manufactured at a low price. It is proposed to characterize this new meter by a clock driven switch cam provided with a plurality of openings for pins each one of which selectively lifts an operator of a switch for stopping an electric circuit. Said switch is mounted on a movable member capable of assuming a forward and a back position, and said movable member is associated with coin operated means for moving said movable member to a back position for a coin passing through the meter in order to move said operator selectively off of a lifting pin so as to restart a cycle. This construction is exceptionally simple, and its operation is simple, in that each pin merely lifts the switch operator for opening the switch, and each coin moves the movable member, and in this way moves the operator off a pin so that the switch closes and starts a new time cycle.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary front view of a coin meter with a fixed cycle constructed in accordance with this invention and illustrated with the front cover removed so that the interior parts may be seen.

Fig. 2 is a plan view of the works of the meter shown in Fig. 1.

Fig. 3 is a sectional view of the works of the meter, this view being taken on the line 3—3 of Fig. 1.

Fig. 4 is a schematic wiring diagram of the meter and an appliance which is operated by the meter.

The coin meter, in accordance with this invention, includes a casing 10 having a coin slot 11. A support 12 is mounted within the casing 10 with several screws 13. This support 12 is provided with a coin chute 14 aligned with said coin slot 11 so that when a coin is dropped through the slot 11 it enters and passes through

2

the chute 14. The coin then falls down into a coin drawer, not illustrated on the drawing. The cover of the casing 10 is also not shown.

A movable member 16 is movably mounted upon the support 12 to move back and forth. More specifically, the movable member 16 comprises a plate pivotally supported at a top corner upon a pintle 17 mounted on and projecting from the support 12. The support 12 comprises a back plate 18 and a front plate 19 spaced from the back plate with spacing strips 20. These plates are joined together as a unit with rivets 21.

A switch cam 23 of insulation material is turnably mounted upon the support 12. More specifically, the switch cam 23 is in the form of an insulation disc which is mounted on a shaft 24 extending through the plate 18 and connected with a clock drive 25 having an electric clock 26. The switch cam 23 is provided with a plurality of openings 27 along its periphery for pins 28 to selectively operate a switch 29.

The switch 29 controls an electric circuit 30. The switch 29 is mounted on said movable member 16. Said switch 29 is provided with an operator 32 extending to a position adjacent the cam 23 for opening the switch 29 for opening the circuit 30 when said operator 32 is lifted from its normal position by one of said pins. The operator 32 is in the nature of a leaf spring which may be flexed upwards. It supports a curved spring 33 which is connected with a flexible arm 34 provided with a contact cooperative with a contact on a stationary arm 35. The switch 29 is illustrated in its closed position. When the operator 32 is moved upwards by a pin 28 (the switch cam 23 turns counter-clockwise) the arm 34 will be flexed downwards and in this way separates the contacts of said switch 29.

The electric clock 26 is connected in series with the switch 29. An appliance 37 or other device intended to be controlled by the meter, is shunted across the clock 26.

The movable member 16 is associated with resilient means for moving it into its front position, in which position said pins 28 may selectively engage and lift said operator 32. This front position is controlled by a stop pin 38 projecting from the support 12 and limiting movement of the movable member 16 towards the left. A tension spring 39 is mounted between the stop 38 and a pin 40 mounted on the movable member 16 by which the movable member 16 is urged towards the left to its front position.

The movable member 16 is also associated with coin operated means to move it to its back posi-

tions, towards the right, for each coin passing said chute 14 in order to move the operator 32 free from one of said pins 28 which lifted it so that the operator 32 may drop back to its normal position to start a new cycle. This coin operated means includes said pin 40 which extends through an opening 41 in the support 12 so as to extend into the chute 14. A disc 42 is turnably mounted at its center upon a pintle 43 mounted on the support 12. A plunger 44 is eccentrically connected with the disc 42 and extends upwards and out through the top of the casing 10. The disc 42 is resiliently urged into a neutral position by a tension spring 45 which is connected with a pin 46 on the disc 42 and with a pin 47 on the support 12. The disc 42 is also provided with a pin 48 which extends through an arcuate slot 49 formed in the support 12 so as to extend through the chute 14. One side of the chute 14 is provided with a curved projecting member 50 around which a coin passing through the chute 14 may travel so that the coin moves towards the right against the pin 40 to move the movable member 16 towards the right. The chute 14 is provided with a recess 52 directly across the curved projecting member 50 to make room for the coin to pass.

The operation of the coin meter may be understood from the following:

Any number of pins 28 may be placed in the openings 27 in order to have the meter operate for preselected times. These pins 28 may be equally spaced from each other or may be placed at unequal distances, as may be desired, for any particular operation of the meter.

The user drops a coin through the slot 11 which then falls downwards through the chute 14 and assumes a position of rest upon the pin 48. The user of the meter now depresses the plunger 44 so that the disc 42 is turned to cause the pin 48 to travel upwards along the arcuate slot 49. The coin is slightly lifted by the pin 48 and then is dropped so that it comes to rest on the projecting member 50. Now the plunger 44 is released and the spring 45 will turn the disc 42 back to its normal position. When the disc 42 turns back, the pin 48 will force the coin against the pin 40 and then will fall down through the chute 14. The coin discharges into a coin receiving box, not shown.

However, when the pin 40 was moved towards the right, the movable member 16 was correspondingly moved so that the operator 32 is moved off the pin 28 which was supporting it. After the coin passes, the movable member 16 moves back to its front position because the spring 39 moves it against the stop 38. The operator 32 is now in its normal position in which the circuit 30 is again closed for starting a new cycle. After a certain length of time the switch cam 23, which is driven by the clock 26, will reach a position in which another one of the pins 28 starts lifting the operator 32. When operator 32 is

lifted a certain amount the cycle will be completed and the switch 29 will again open. This opens the circuit 30 and the clock 26 and the appliance 37 stops operating. A new coin must now be inserted in the meter to restart operation of the clock 26 and the appliance 37, and in this way the operation can be repeated. In this meter a coin must not be dropped into the meter before a cycle is finished, because the coin will merely be lost as the operator 32 will not drop off a lifting pin 28 unless said pin 28 is in a position in which the cycle is completed.

While I have illustrated and described the preferred embodiment of my invention, it is to be understood that I do not limit myself to the precise construction herein disclosed and the right is reserved to all changes coming within the scope of the invention as defined in the appended claims.

Having thus described my invention, what I claim as new and desire to secure by United States Letters Patent is:

1. A coin meter with a set cycle, comprising a casing, a support mounted in said casing, a movable member movably mounted on said support to move back and forth, a switch cam turnably mounted on said support, a switch for controlling an electric circuit mounted on said movable member and having an operator extending to a position adjacent said cam for opening said circuit when lifted from normal position, pins on said switch cam for selectively lifting said operator to actuate said switch, clock means having an electric clock controlled by said circuit for driving said switch cam in order to engage said pins selectively with said operator to actuate said switch, resilient means for urging said movable member into a front position in which said pins may selectively engage and lift said operator, and means for moving said movable member to a back position for moving said operator free from a pin which lifted it at the end of a cycle so that it may drop to normal position.

2. A coin meter, as defined in claim 1, in which said switch cam has a plurality of openings for selectively receiving said pins.

3. A coin meter as defined in claim 1, in which said resilient means comprises a spring acting between said movable member and said support.

HARRY GREENWALD.
